PHOTOGRAPHIC BORDER PRINTER OR THE LIKE

Charles Scott, 2144-A W. Juno Ave.,
Anaheim, Calif. 92804

Filed Nov. 9, 1964, Ser. No. 82,520

Term of patent 3½ years

(Cl. D61—1)

FIG. 1.

FIG. 2.

FIG. 3.

FIG. 4.

FIG. 5

FIG. 6

FIG. 1 is an isometric view of a photographic border printer or the like showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left end elevational view thereof.

The dominant features of my design reside in the specific configuration of the plates in combination with a ball-like element which are mounted on the top of a rectangular casing all as shown.

I claim:

The ornamental design for a photographic border printer or the like, substantially as shown and described.
